Primary Examiner — Lauren D McVey(74) *Attorney, Agent, or Firm* — Design IP(57) **CLAIM**

The ornamental design for a display support, as shown and described.

DESCRIPTION

FIG. 1 is a front perspective view of a display support showing our new design;

FIG. 2 is an alternate front perspective view thereof;

FIG. 3 is a rear perspective view thereof;

FIG. 4 is an alternate rear perspective view thereof;

FIG. 5 is a front elevation view thereof;

FIG. 6 is a rear elevation view thereof;

FIG. 7 is a left side elevation view thereof;

FIG. 8 is a right side elevation view thereof; and,

FIG. 9 is a top plan view thereof.

The broken lines immediately adjacent to the shaded areas in FIGS. 1-9 depict the bounds of the claimed design, while all other broken lines are directed to environment. The broken lines form no part of the claimed design. In addition, the unshaded surfaces that directly adjoin the claimed solid line edges form no part of the claimed design. The bottom view is omitted and forms no part of the claimed design.
